JOHN J. CHAPIN, OF DETROIT, MICHIGAN, ASSIGNOR TO BURROUGHS ADDING MACHINE COMPANY, OF DETROIT, MICHIGAN, A CORPORATION OF MICHIGAN.

TABULATING MECHANISM FOR ADDING-MACHINES.

1,135,500.

Specification of Letters Patent. Patented Apr. 13, 1915.

Application filed June 9, 1910. Serial No. 566,022.

To all whom it may concern:

Be it known that I, JOHN J. CHAPIN, a citizen of the United States, residing at Detroit, in the county of Wayne and State of Michigan, have invented a certain new and useful Improvement in Tabulating Mechanism for Adding-Machines, of which the following is a specification.

The invention relates to adding machines or other recording machines which are adapted to produce tabulated work upon paper supported in a laterally shiftable carriage such *e. g.* as that commonly employed in adding machines and typewriting machines wherein the paper overlies a roller platen.

The chief object of the present invention is to provide for automatically shifting the carriage in columnar positions without regard to any regular order or succession of columns. Thus the operator of the machine, tabulating a miscellaneous collection or series of items can by the mere depression of a selected key cause the carriage to automatically move to any columnar position within the range of its capabilities, whether such columnar position is in advance of others or is one precedent to that last occupied, and if the carriage in moving from one columnar position to another is required to pass one or more intermediate columnar positions it will travel the whole distance backward or forward automatically without requiring repeated manipulation of a key or other controlling device, the movement however extensive being continuous as distinguished from a step by step movement. It is obvious that an arrangement of this sort will provide for more readily and expeditiously tabulating miscellaneous items which do not occur in regular order as related to the succession of columns across a sheet of paper.

With the above and incidental objects in view the invention consists in certain novel features of construction and combinations of parts the essential elements whereof are recited in the appended claims, and the preferred form of embodiment of which is described in detail hereinafter and illustrated in full in the accompanying drawings which form part of this specification.

Of said drawings Figure 1 represents an adding machine of the well known Bur-

roughs type having applied thereto a tabulating mechanism embodying the present invention, the machine being represented in left side elevation with the usual inclosing casing removed and parts of the supporting frame work broken away; Fig. 1^a is a detail vertical cross sectional view on line 1^a—1^a of Fig. 1; Fig. 2 is a sectional left side elevation of the rear portion of the machine on an enlarged scale as compared with Fig. 1; Fig. 3 is a rear elevation of the lower portion of the machine, the carriage being shown in the last columnar position of the series of such positions provided for by the equipment here shown, which condition corresponds with that represented in Figs. 1 and 2; Figs. 4 and 5 are views somewhat similar to Fig. 3 being in a large part rear elevations of the lower back portion of the machine, but the condition represented in Fig. 4 differs from that represented in Fig. 3 in that the relation between certain parts has been changed by depression of a tabulating key; the view also differs from Fig. 3 in that certain clutches and reversing gearing appear in longitudinal section; in Fig. 4 a still different condition is represented, namely that which obtains when the carriage is moved to the extreme in one direction and is about to reverse its movement. Fig. 6 is a vertical sectional view from front to rear of a portion of the machine embracing parts concerned in the line spacing of the paper; Fig. 7 is a sectional plan view taken substantially on the line 7—7 of Fig. 6; Fig. 8 shows the keyboard of the machine in plan.

It will be unnecessary to describe the adding machine proper which is not vitally concerned in the operations of the tabulating mechanism of the present invention. The latter is not dependent upon the presence of adding mechanism or upon the presence of any particular type of recording mechanism though of course in practice it would necessarily be employed with some sort of recording devices. It will suffice therefore to merely point out a few of the well known elements of the adding machine proper which is here shown as of the well known Burroughs type. The usual keys for setting up amounts are designated by the numeral 291 and the type plates, which correspondingly present the amount at the

printing line, are designated by the numeral 618.

The roller platen is designated by the numeral 17 and occupies the usual position at the rear of the machine being carried by a laterally shiftable carriage 2 running upon roller bearings of a bracket 3 secured to the frame work of the machine. The shifting of this carriage is done by a motor through the medium of friction clutches and reversing gearing. In the present instance an electric motor is coupled to a worm 5 and the latter engages a worm wheel 6 secured to a shaft 7 which is journaled in side arms 8^a of a bracket 8 on the back of the machine frame. Clutch disks 9 and 9^a have grooved hubs 10 and 10^a sliding upon said shaft and carrying pins 11 and 11^a sliding in collars 12 and 12^a which are fast with the shaft and consequently rotate said clutch disks constantly. The latter are faced with friction rings 13 and 13^a which confront clutch disks 14 and 14^a loose upon the shaft and secured respectively to the hubs of bevel gears 15 and 15^a. Springs 16 and 16^a, surrounding the shaft between the disks of the two clutches tend to force them apart and do so normally as illustrated in Fig. 3, so that no movement is imparted to the gears 15 and 15^a. These gears both mesh with a bevel gear 17 secured to the lower end of a shaft 18 journaled in arms 8^c and 8^d of the bracket 8 and carrying at its upper end a spur gear pinion 19 in mesh with the rack 20 on the carriage 2.

Between depending and rearwardly extending portions 3^a of the end pieces of the fixed bracket 3 there extends a rock shaft 21 which carries spaced along it a series of tabulator stop fingers 22 spirally disposed as illustrated in Figs. 1 and 2, so that by turning the shaft 21 more or less one or another of these fingers may be brought into effective position, which, under the organization here shown, is the upright position which the near end finger occupies in Figs. 1 and 2. On the carriage there are pivoted two pass-by stop pieces 23 connected by a spring 24 which normally holds them against stop pins with their end edges confronting each other and spaced apart as shown in Fig. 3 so as to receive between them any one of the fingers 22. It will be obvious that the carriage moving in either direction will be stopped by the encounter of one or the other of these pieces 23 with the stop finger 22 which is occupying the effective position and furthermore that the engagement of such stop finger between the two pieces 23 will insure a stable columnar position of the carriage.

The turning of the shaft 21 to bring one or another of the stop fingers 22 into effective position is accomplished by depression of keys 25 extending in a series from front

to rear at the left of the amount keyboard (see Fig. 8), the numbered to indicate columns counting from the left to the right. Thus in the present instance where six columns are provided for, the keys are numbered from one to six beginning at the front. These keys surmount stems 26 sliding through the familiar keyboard plates 212 and 213 and also sliding through a specially provided plate 27 at their lower ends and being upheld by springs 28. Rollers 29 at the lower ends of these stems are adapted to coöperate respectively with double inclined differential cam projections 30 on a bar 31 which is mounted to slide backward and forward being slotted to engage screws 32 entering portions of the frame work of the machine. At its rear end this bar 31 has rack teeth 33 in its upper edge engaging a gear wheel 34 secured to the left-hand end of the shaft 21. The rear inclined edges of the cam projections 30 are graded in angularity and so likewise are the front inclined edges of said cam projections, so that the keys act with uniformly increasing effect to shift the bar 31. Thus said bar having been moved all the way forward by depression of the 6 key as represented in Fig. 1, the 5 key will move the bar backward the least distance, or what may be considered a unit of movement. The 4 key will move it twice as far, the 3 key three times as far and so on, and of course the stop projections 22 will be positioned accordingly. Here the forward inclined edges of the cam projections are concerned, whereas if the bar has been shifted all the way rearward by depression of the 1 key, then of course the rear inclined edges of the cam projections will be brought below the rollers 29 respectively and conditions are reversed in that movement of the bar lessens as the keys 25 extend rearward. This means of course that the rear inclined edges of the cam projections are reversed as to relative angularity as compared with the series of front inclined edges of said cam projections. At the bases of the cam projections rounded sockets 33 are formed for the rollers 29 to seat in thereby insuring an exact positioning of the shiftable bar and consequently of the tabulator projection 22 which is to control the position of the carriage. To guard against any shifting of the bar 31 when the keys are disengaged therefrom, a series of saw teeth 34 are formed in the under edge of the bar as shown in Fig. 1 and engaged by a spring-held pawl 35, the engagement of whose V-shaped nose with one or another of the notches between the saw teeth 34 causes sufficient friction to prevent accidental shifting of the bar.

It is thought that it will now be perfectly obvious how a columnar position of the carriage can be determined by depression of a selected key 25 which act results through the

medium of the device above described, in disengaging one finger 22 from the stop pieces 23 and bringing another of the stop fingers 22 into line with said stop pieces so that when the carriage moves one way or the other one of these stop pieces 23 will wipe past the newly positioned stop finger and the other stop piece will abut against such finger which will then be confined between the stop pieces and will hold the carriage against movement in either direction.

The motor connections hereinbefore described for propelling the carriage one way or the other are under control of the tabulator keys 25 through the medium of devices now to be described. Besides the rollers 29 on the stems of said keys there are rollers 36 projecting oppositely to said rollers 29 (see Fig. 1*), and adapted to act with uniform effect upon corresponding rear inclined edges of cam projections 37 on a sliding bar 38 extending similarly to the bar 31, being slotted at its forward end to embrace the same screw 32 which occupies the forward end of the said bar 31 (see Figs. 1 and 1*). The rear end of this bar 38 is upturned as shown in Fig. 1 and pivotally connected to the upstanding arm of a bell crank lever 40 which is pivoted upon the screw 32 occupying the slot at the rear end of the bar 31. The rearwardly-extending arm of this bell crank lever 40 engages under a roller 41 on the end of the horizontally-extending arm of another bell crank lever 42 working in a plane at right angles to the bell crank lever 40, see Fig. 3, this bell crank lever 42 being pivoted at 43 to the back of the machine. A latch lever 44 of bell crank form is pivoted at 45 to the downwardly extending arm of the bell crank lever 42 and has a catch shoulder 46 normally engaging a pin 47 on the upper arm of a clutch closing lever 48 pivoted in a bifurcated post on one of the bracket arms 8* and forked to embrace the sleeve or hub 10 of the clutch disk 9, the fork having pins or studs occupying the groove of said hub. It follows from the form and arrangement of parts just above described, that depression of any one of the keys 25 causes a forward thrust of the bar 38 and consequently upward movement of the rearwardly-extending arm of the bell crank 40 and corresponding movement of the horizontally-extending arm of the bell crank 42 and consequent swinging of the downwardly extending arm of the latter bell crank in a direction to cause the latch lever 44 to operate the clutch lever 48 and force the clutch disk 9 into frictional engagement with the companion clutch disk 14. This will obviously result in propulsion of the carriage by the motor in a direction ordained by the gearing connections hereinbefore described. The motor-driven worm 5 rotates constantly in the direction indi-

cated by the arrow in Fig. 2 and so the result of closing the clutch as above described will be to propel the carriage to the left as the machine would be viewed from the front, which of course means to the right as the machine is viewed from the rear as in Fig. 3. If at the time of depressing one of the tabulator keys 25 the carriage is not at the extreme columnar position illustrated in Fig. 3 and is to move to a columnar position farther to the left than it is occupying at the time the key is depressed, then the effect will be simply such as above described, that is to say, the tabulator stop finger 22 which has been holding the carriage at a certain columnar position will be disengaged from the carriage and the latter will move on to the left until it encounters the newly set stop finger whether it be the next one on the shaft 21 or a stop finger farther on. However, if the new columnar position which the carriage is to occupy is farther to the right than the columnar position it already occupies, then obviously something further is required to take place for the carriage must necessarily shift the other way. According to the present invention as here carried out, the carriage would not immediately shift in the reverse direction, under the circumstances just mentioned, but would first travel to the extreme of its movement leftward and then automatically reverse and travel back to the newly positioned stop finger. It is obvious that when the shaft 21 is rocked in a direction to carry a higher numbered column stop finger out of effective position and bring a lower numbered column stop finger into effective position, the carriage is necessarily released for movement leftward unobstructed by a column stop finger since the stop pieces 23 are already leftward of the newly positioned column stop finger. Thus rocking of the shaft 21 in the direction of the arrow, Fig. 2, disengages the sixth column stop finger from the carriage and leaves the latter free to move farther leftward, the newly positioned column stop finger being located to the right so that it necessarily awaits a return movement of the carriage in order to perform its function of locating the carriage in a new columnar position.

The arrangement for automatically reversing the movement of the carriage under control of the tabulator keys, is of the following description: The before-mentioned lever 44 is pivotally connected at its upper end with a bar 50 which extends horizontally and has an upturned end 50* standing in the path of movement of a plate or finger 52 secured to and depending from the right-hand end of the carriage. The result is that when the carriage is released under such circumstances as above mentioned so it moves beyond the last columnar position, this plate 130

or finger 52 strikes the upturned end of the tappet bar 50 disengaging the latch lever 44 from the clutch operating lever 48 as illustrated in Fig. 5, whereupon the carriage advancing clutch opens. Immediately thereupon the other clutch closes so that the carriage will be returned. The hub 10^a of this other clutch is embraced by the forked end of a lever 53 pivoted to a bifurcated post on one 10 of the side pieces 8^a of the bracket 8, and equipped with studs or pins occupying the groove of said hub. A spring 54 applied to this lever tends to swing it in a direction to close the clutch but is normally restrained 15 by a latch lever 55 which is pivoted to the arm 8^a of the bracket 8 and has a catch shoulder 56 engaging a pin 57 on said clutch operating lever 53. The upper end of the latch lever 55 is pivotally connected to the 20 tappet bar 50. Consequently, when said bar is shifted as before described it not only disengages the latch lever 44 from the clutch operating lever 48, but also disengages the latch lever 55 from the clutch operating 25 lever 53. The catch shoulder 56 of this latch lever 55 is elongated as compared with the catch shoulder 46 of the latch lever 44, for the purpose of delaying the release of the clutch operating lever 53 until after the 30 clutch operating lever 48 has been released thus insuring that the carriage advancing clutch shall open before the carriage returning clutch closes. Fig. 5 illustrates the condition when the carriage is about to start 35 back.

In order to provide for the opening of the carriage returning clutch when it has fully performed its function, the clutch operating lever 53 is operatively connected with the 40 bell crank lever 42 so that upon release of the tabulator key and consequent return to normal of said bell crank lever 42 by its spring 42^a, the said clutch operating lever will be swung back to its original position 45 opening the clutch. To this end a lever 60 is pivoted to a portion of the bracket 8 and coupled on opposite sides of its pivot with two links 61, 62, the former coupled to the downwardly extending arm of the bell crank 50 42 and the link 62 slotted to engage a stud at the upper end of the clutch lever 53. (The slot provides for the preliminary movement of the lever and links resulting from depression of the tabulator key, without such movement affecting the clutch lever or being interfered with by the latter). It results that when the bell crank lever 42 returns to normal it will operate the lever 53 against the stress of the latter's spring 54 60 and open the clutch, it being understood of course that the spring 42^a is superior to the spring 54.

A spring 44^a applied to the latch lever 44 serves to restore the latter and the tappet 65 bar 50 and the latch lever 55 when the car-

riage has moved to the right, said latch levers reengaging respectively with the clutch lever pins 47 and 57. Vibration of the bell crank lever 42 does not materially affect the tappet bar 50 because the point of connection between the latter and the latch lever 44 is close to the pivot 43 of said bell crank lever.

It will be obvious that with a tabulating arrangement such as above described, having 75 for its purpose promiscuous selection of columnar positions, there should be no automatic line spacing in the sense of line spacing without intervention by the operator. On the contrary it is desirable that 80 line spacing shall occur only as predetermined by the operator since the last item in the horizontal series may occur at any columnar position. To this end a special key is provided for the operator to use 85 whenever he has filled out one horizontal line and desires to start another. In this connection it may be stated furthermore that it is preferable that the line spacing take 90 place in the same operation which prints the first item of a new horizontal line, rather than in the operation which prints the last item in the preceding horizontal line. There is less likelihood of a failure to line space if the construction of the machine provides for 95 the line spacing being done in connection with the starting of a new horizontal line, than if it is done with the printing of the last item of the preceding horizontal line for of course the operator would be more 100 likely to think of the necessity for line spacing when starting a new series of items than when completing a series by the printing of an item at any one of a number of columnar 105 positions. Therefore the line spacing mechanism of the present machine is modified as compared with line spacing mechanism heretofore used in this class of machines, so as to provide for line spacing during the forward pull of the operating handle instead 110 of during the return movement thereof.

Referring to Figs. 1, 6 and 7 the reference numeral 60 designates a line spacing lever similar to that ordinarily employed in these machines, the same carrying a roller 60^b at 115 its forward end and being coupled at its rear end to a slide 61^a arranged to reciprocate vertically on the back panel of the machine and vibrating a bail 62^a. The latter is secured to a rock shaft 63 which has an arm 64 connected by a link 65 with a pawl-carrying arm 66 loose on the platen shaft 67 and carrying a spring-held pawl 68. A ratchet wheel 69 is secured to the platen and the pawl is adapted to act upon said ratchet wheel upon such movement of the lever 60 as would ordinarily take place when the handle of the machine is pulled forward. (This is the reverse of the usual arrangement where movement of said lever so ef- 120 125 130

fected retracts the pawl and upon return movement of the lever accompanying return of the operating handle, the pawl takes effect to turn the platen). An adjustable 5 shield 70 is here shown for regulating the extent to which the pawl 68 will turn the roller platen.

In order to provide for controlling the effectiveness of the line spacing mechanism 10 so that it will act or not according to the election of the user, a modified form of cam for co-acting with the lever 60 is employed. Ordinarily the roller 60^b occupies a cam slot 15 of a cam piece secured to the rock shaft 100 so that in every operation of the machine the lever 60 is vibrated. In the present instance there is a cam piece 121 fastened to said shaft 100 but instead of having such a cam slot it has 20 an interior edge 121^a corresponding only with one side of such slot, and is opened out in the center and formed with an opposite interior edge 121^b which is concentric with the shaft 100. A spring 72 applied to the 25 lever 60 tends to rock the same so as to effect line spacing as governed by the cam edge 121^a upon oscillation of the shaft 100 produced by forward pull of the operating handle. However, said spring is normally 30 prevented from so affecting said lever 60^a and in consequence the concentric edge 121^b travels in contact with the roller 60^b and there is no movement of said lever 60^a. This 35 restraint of the latter is effected through the medium of an arm 73 secured to the same shaft 60^c to which the said lever 60 is secured, see Fig. 7, said arm having a pin or stud 73^a at its upper end (Fig. 6) normally engaged with a latch arm 74. The spring 72 40 is directly applied to a forward branch of the arm 73 and obviously tends to rock the latter rearward and the lever 60^a correspondingly so as to effect the line spacing. Said spring being attached at its opposite 45 end to the latch arm 74 also serves to enforce engagement between the latter and the stud 73^a. This latch arm is part of a lever, the other arm 75 of which is coupled to the stem 76 of a key 77 projecting on the keyboard in line with the tabulator keys 25, see Fig. 8. Obviously the spring 72 normally upholds 50 this key. It is clear that depression of the key against the stress of said spring will disengage the latch arm 74 from the stud 73^a and so free the arm 73 and lever 60^a. To avoid having to hold the key down 55 throughout the operation, a latch is provided for detaining the arm 74, said latch being in the form of a lever 78 having a catch shoulder 78^a adapted to engage a stud 74^a on the arm 74, as illustrated by dotted lines in Fig. 6. A spring 79 applied to the lever 78 enforces the engagement. A downward extension 60 of the latch lever 78 having a curved rear edge for engagement with the stud 74^a,

and a similar rearward extension of the latch arm 74 for engagement with the stud 73^a, will preserve the proper relation of parts in operation.

It will be obvious from what has been 70 above explained that when the key 77 is depressed and the machine then operated the rearward rocking of the cam piece 121 will be accompanied by a rocking of the lever 60^a and a turning forward of the roller platen. 75 Then of course with the return of the operating handle the forward rocking of said cam piece will retract the pawl. To provide for re-locking of the lever 60^a at the conclusion of the operation, the latch lever 78 is 80 extended upward for engagement with a stud 80 carried by the familiar vibratory amount key restoring bail 202.

To provide for having the line spacing mechanism operate repeatedly as when single column work may be in progress, the key stem 76 is formed with a notch 76^a adapted to engage under the upper keyboard plate 212, the lower keyboard plate 213 being slotted to permit the necessary rearward 90 movement of the key stem. A comparatively light spring 81, applied to the key stem 76, prevents the notch from so engaging with the upper keyboard plate 212 unless the operator forcibly thrusts the key rearward 95 after fully depressing it.

What I claim is:

1. The combination with a laterally shiftable paper carriage capable of occupying any one of a plurality of columnar positions, and automatically reversing means for propelling it in both directions; of column-determining and propelling-means-controlling devices including provisions for effecting automatic shift of the carriage from an advanced columnar position to any precedent columnar position by continuous motor action.

2. The combination with a laterally shiftable paper carriage capable of occupying any one of a plurality of columnar positions, and a unitary motor means for propelling it in both directions; of column-determining and motor-means-controlling devices including double-acting column-stops for variously limiting movement of the carriage in either direction, and provisions for automatically reversing the movement of the carriage.

3. The combination with a laterally shiftable paper carriage capable of occupying any one of a plurality of columnar positions, motor means for driving the same, reversible clutch mechanism intermediate the motor means and the carriage, and column-determining and clutch-controlling devices for effecting the shift of the carriage from an advanced to a preceding columnar position.

4. The combination with a laterally shiftable paper carriage capable of occupying

85

90

95

100

105

110

115

120

125

130

any one of a plurality of columnar positions, motor means for driving the same, automatically reversing clutch mechanism intermediate the motor means and the carriage, and column-determining and clutch-controlling devices for effecting shift of the carriage from an advanced to a preceding columnar position.

5. The combination with a laterally shiftable paper carriage capable of occupying any one of a plurality of columnar positions, motor means for driving the same, reversible clutch mechanism intermediate the motor means and the carriage for engaging the same to drive the carriage, manually operable means for engaging the clutch mechanism to shift the carriage in one direction, automatic means for reversing the clutch to drive the carriage in the opposite direction, and means for arresting the carriage at any desired columnar position.

6. The combination with a laterally shiftable paper carriage capable of occupying any one of a plurality of columnar positions, motor means for driving the same, reversible clutch mechanism intermediate the motor means and the carriage, and column-determining and clutch-controlling devices including double-acting column stops for variously limiting the movement of the carriage in either direction.

7. The combination with a laterally shiftable paper carriage capable of occupying any one of a plurality of columnar positions, and motor means for propelling it in both directions; of column-determining and motor-means-controlling devices automatically controlling the motor to advance the carriage from an advanced columnar position to the limit of movement in the one direction and then automatically return the carriage to a precedent columnar position.

8. The combination with a laterally shiftable paper carriage capable of occupying any one of a plurality of columnar positions, automatic reversing means for propelling it in both directions, column-determining and motor-means-controlling devices including double-acting column-stops for variously limiting movement of the carriage in either direction, and keys for differentially positioning said stops.

9. The combination of a laterally shiftable paper carriage capable of occupying any one of a plurality of columnar positions, and automatically reversing means for propelling it in both directions; of column-determining and motor-means-controlling devices including double-acting column-stops for variously limiting movement of the carriage in either direction, keys for differentially positioning said stops and starting the propelling means to advance the carriage, whereby the latter may be advanced beyond an advanced columnar position, upon opera-

tion of a key pertaining to a precedent columnar position, and then returned automatically to such precedent columnar position.

10. The combination with a laterally shiftable paper carriage capable of occupying any one of a plurality of columnar positions, and a motor; of reversing drive connections between the motor and the carriage; and column-determining and drive-connections-controlling devices including provisions for effecting automatic shift of the carriage from an advanced columnar position to either one of several precedent columnar positions.

11. The combination with a laterally shiftable paper carriage capable of occupying any one of a plurality of columnar positions, and a motor; of reversing drive connections between the motor and the carriage; and column-determining and drive-connections-controlling devices including double-acting column-stops for variously limiting movement of the carriage in either direction, and provisions for automatically reversing the drive connections.

12. The combination with a laterally shiftable paper carriage capable of occupying any one of a plurality of columnar positions, and a motor; of automatically reversing drive connections between the motor and the carriage; and column-determining and drive-connections-controlling devices including double-acting column-stops for variously limiting movement of the carriage in either direction, and provisions for controlling the motor and connections to cause them to automatically advance the carriage from an advanced columnar position to the limit of movement in the one direction and then automatically return the carriage to a precedent columnar position.

13. The combination with a laterally shiftable paper carriage capable of occupying any one of a plurality of columnar positions, and a motor; of reversing drive connections between the motor and the carriage; and column-determining and drive-connections-controlling devices including double-acting column-stops for variously limiting movement of the carriage in either direction, keys for differentially positioning said stops, and provisions for automatically reversing the drive connections.

14. The combination with a laterally shiftable paper carriage capable of occupying any one of a plurality of columnar positions, and a motor; of reversing drive connections between the motor and the carriage; and column-determining and drive-connections-controlling devices including double-acting column stops for variously limiting movement of the carriage in either direction, keys for differentially positioning said stops, and effecting the motor drive connections to advance the carriage, and provi-

- sions for automatically reversing the drive connections whereby the latter is adapted to advance beyond an advanced columnar position, upon operation of a key pertaining 5 to a precedent columnar position, and then return automatically to such precedent columnar position.
15. The combination with a laterally shiftable paper carriage capable of occupying any one of a plurality of columnar positions, and a motor; of reversing drive connections between the motor and the carriage comprising a pair of oppositely acting clutches; and column-determining and 10 clutch controlling devices including provisions for effecting automatic shift of the carriage from an advanced columnar position to either one of several precedent columnar positions.
20. 16. The combination with a laterally shiftable paper carriage capable of occupying any one of a plurality of columnar positions, and a motor; of reversing drive connections between the motor and the carriage 25 comprising a pair of oppositely acting clutches; and column-determining and clutch controlling devices including double-acting column-stops for variously limiting movement of the carriage in either direction, 30 and provisions for automatically reversing the drive connections.
17. The combination with a laterally shiftable paper carriage capable of occupying any one of a plurality of columnar positions, and a motor; of automatically reversing drive connections between the motor and the carriage comprising a pair of oppositely acting clutches; and column-determining and clutch controlling devices including 35 double-acting column-stops for variously limiting movement of the carriage in either direction, and provisions for controlling the drive connections to automatically advance the carriage from an advanced columnar 40 position to the limit of movement in the one direction and then automatically return the carriage to a precedent columnar position.
45. 18. The combination with a laterally shiftable paper carriage, capable of occupying any one of a plurality of columnar positions, and a motor; of reversing drive connections between the motor and the carriage comprising a pair of oppositely acting clutches; and column-determining and 50 clutch controlling devices including double-acting column-stops for variously limiting movement of the carriage in either direction, keys for differentially positioning said stops, 55 and provisions for automatically reversing the clutches.
60. 19. The combination with a laterally shiftable paper carriage, capable of occupying any one of a plurality of columnar positions, and a motor; of reversing drive connections between the motor and the carriage 65 comprising a pair of oppositely acting clutches; and column-determining and clutch controlling devices including double-acting column-stops for variously limiting movement of the carriage in either direction, keys for differentially positioning said stops, 70 and provisions for automatically opening that clutch and closing the other clutch to reverse the movement of the carriage, whereby the latter may be advanced beyond an advanced columnar position, upon operation of a key pertaining to a precedent columnar position and then returned automatically to such precedent columnar position.
75. 20. The combination with a laterally shiftable paper carriage, capable of occupying any one of a plurality of columnar positions, and a motor; of reversing drive connections between the motor and the carriage comprising a pair of oppositely acting clutches; and column-determining and clutch-controlling devices including double-acting column-stops for variously limiting 80 movement of the carriage in either direction, keys for differentially positioning said stops, a member for closing the carriage-advancing clutch, key connections latched to said member, a carriage-operated tappet for unlatching said connections, a normally restrained member for closing the carriage-returning clutch, means for releasing said last mentioned member by the tappet and means for retracting it by the key connections upon restoration thereof to normal; whereby the carriage may be advanced beyond an advanced columnar position, upon operation of a key pertaining to a precedent columnar position, and then returned automatically to such precedent columnar position.
85. 21. The combination with a laterally shiftable paper carriage capable of occupying any one of a plurality of columnar positions, and a motor; of reversing drive connections between the motor and the carriage comprising a pair of oppositely acting clutches; and column-determining and clutch-controlling devices including double-acting column-stops for variously limiting 90 movement of the carriage in either direction, keys for differentially positioning said stops, a lever applied to the carriage-advancing clutch to close the same, a key-actuated bell-crank, a latch on the latter engaging said clutch lever, a lever applied to the carriage-returning clutch and tending to close it, a latch normally restraining said last-mentioned clutch lever, a tappet bar connected 95 to the two latches, and a lever and link connection between the bell-crank and the second-mentioned clutch lever; whereby the carriage may be advanced beyond an advanced columnar position, upon operation 100.
105. 110. 115. 120. 125.

of a key pertaining to a precedent columnar position to strike the tappet bar; substantially as and for the purpose described.

22. The combination with a laterally shiftable paper carriage, capable of occupying any one of a plurality of columnar positions, and a motor; of reversing drive connections between the motor and the carriage comprising a pair of oppositely acting clutches; and column-determining and clutch-controlling devices including double-acting column-stops for variously limiting movement of the carriage in either direction, keys for differentially positioning said stops, a member for closing the carriage-advancing clutch, a cam-bar actuated by said keys; a bell crank lever connected to said bar, a second bell crank lever engaged by the first and latched to said member, a carriage-operated tappet for unlatching the latter, a normally restrained member for closing the carriage-returning clutch, means for releasing said last-mentioned member by the tappet and means for retracting it by the key connections upon restoration thereof to normal; whereby the carriage may be advanced beyond an advanced columnar position, upon operation of a key pertaining to a precedent columnar position, and then returned automatically to such precedent columnar position.

23. The combination with a laterally shiftable paper carriage capable of occupying any one of a plurality of columnar positions, and a motor; of reversing drive connections between the motor and the carriage comprising a pair of oppositely acting clutches; and column-determining and clutch-controlling devices including double-acting column-stops for variously limiting movement of the carriage in either direction, keys for differentially positioning said stops, a lever applied to the carriage-advancing clutch to close the same, a cam-bar actuated

by said keys, a bell crank lever connected to said bar, a second bell crank lever engaged by the first, a latch on said second bell crank lever engaging said clutch lever, a lever applied to the carriage-returning clutch and tending to close it, a latch normally restraining said last-mentioned clutch lever, a tappet bar connected to the two latches, and a lever and link connection between the second bell-crank and the second-mentioned clutch lever; whereby the carriage may be advanced beyond an advanced columnar position, upon operation of a key pertaining to a precedent columnar position to strike the tappet bar; substantially as and for the purpose described.

24. The combination of a laterally shiftable paper carriage having opposed pass-by stop-projections; a shaft in fixed bearings and carrying a spiral series of stop fingers and a gear; a slide-bar having rack teeth engaging said gear and a series of differentiated double-inclined cam projections; and a set of depressible keys adapted to act upon said cam projections respectively in the manner and for the purpose described.

25. The combination of a laterally shiftable paper carriage having opposed pass-by stop-projections; a shaft in fixed bearings and carrying a spiral series of stop fingers and a gear; a slide-bar having rack teeth engaging said gear and a series of differentiated double-inclined cam projections; a set of depressible keys adapted to act upon said cam projections respectively, a second cam bar arranged to be actuated by said keys; and reversible carriage propelling means controlled by said second bar and by the carriage itself.

JOHN J. CHAPIN.
